UNITED STATES PATENT OFFICE.

GEORGE HALL-BULLOCK, OF LONDON, ENGLAND, ASSIGNOR TO ARTHUR MARKS
COULSON, OF LONDON, ENGLAND.

INTERNAL-COMBUSTION MOTOR.

Application filed January 14, 1922. Serial No. 529,308.

To all whom it may concern:

Be it known that I, GEORGE HALL-BULLOCK, a subject of the King of Great Britain and Ireland, residing at London, England, have invented certain new and useful Improvements in Internal-Combustion Motors, of which the following is a specification.

This invention relates to internal combustion motors, and is especially applicable to such motors as operate upon the two-stroke cycle.

The invention has for its object to provide an improved construction of motor which may be manufactured at a low cost, and which may be easily and expeditiously assembled either in single or multiple cylinder units as required.

The invention consists in the improved internal combustion motor to be hereinafter described.

Referring now to the accompanying drawings, which illustrate the invention and form part of this specification.

Figures 1 and 2 show sectional elevations at right angles to one another of an air-cooled single cylinder two-stroke motor constructed according to the invention, while

Figure 3 shows a sectional plan with the piston removed, the section being taken through the line 3—3 on Figure 2.

Figure 4 shows a longitudinal sectional elevation of an air-cooled two-cylinder unit of the two-stroke type, constructed according to the invention, while

Figure 5 shows a plan of the motor unit shown in Figure 4.

In the drawings similar parts are, when desirable, denoted by the same reference numerals.

In carrying the invention into effect, according to one form, and as applied by way of example to an air-cooled two-stroke motor having a single cylinder, the cylinder 1, Figures 1, 2 and 3, crank case, 2, and crank shaft bearing supports 3, are formed, integrally with one another, as a single casting, or built up as a unit.

The cylinder is provided with radiating fins or flanges 4, in the present example, but a suitable water-jacket and passages may be provided instead of the fins when a water-cooled cylinder is desired.

Admission, exhaust and transfer ports 5,

6 and 7, respectively, in Figures 2 and 3, of the usual type, are formed in the cylinder 1, and are adapted to be opened and closed in their proper sequence by the piston 8.

The admission and exhaust ports are provided with short external pipes 9 and 10 respectively, cast integrally with the cylinder 1, the overall length of the pipes being the same as the overall length of the unit. The exhaust pipe is provided with radiating fins 10.

Within the exhaust pipe 10, a tube 11, Figures 2 and 3, is disposed the tube being threaded at one end of the pipe, and provided with a shoulder 13, at the other end thereof.

The tube is formed with a hole 14, opposite to the exhaust duct 6, and is clamped in position by the screwed cap 15; a similar tube 16 is provided for the induction pipe 9.

In the bottom of the crank case 2, a threaded hole is formed for the introduction of the piston and its associated parts and is adapted to be closed by a correspondingly threaded cover 17, so as to form a pressure-tight joint.

The crank case 2, as is usual in two-stroke motors, forms a compression chamber for the charge.

Bushings 18, for the crank shaft are disposed in the supports 3, which are arranged at right angles to the axis of the cylinder as shown. Each of the end faces of the crank case 2 are provided with an annular extension 19, which co-acts with the flange 20 of the dished cover plate 21. The plates 21 are provided with a support 22 for the crank shaft bushings or bearings 18, and form an annular lubricating chamber 23, round the crank shaft bushes or bearings at each end of the crank case.

The crank case 2 is formed with double walls on its peripheral portions, the space 24 between the walls forming a chamber which acts as a reservoir for lubricant and which may be connected to the annular lubricating chambers 23, by pipes or ducts for leading the lubricant thereto.

In the space 24 between the double walls of the crank case, four solid web portions 25 are formed, the web portions being bored to accommodate through-going bolts 26, which clamp the cover plates 21 firmly to the crank case 2.

The crank case 2 is also provided with lugs or brackets 27, for attaching the motor to the chassis or bedplate.

The crank webs 28 with their balance weights 29, and crank pin 30, connecting rod 31, gudgeon pin 32, and piston 8, are of the usual type and are assembled as a unit. The crank webs 28 may either be formed integrally with the crank pin 30 as shown, or 10 they may be built up therewith by any of the usual methods.

The crank webs 28 are formed with tapered holes for the reception of the correspondingly formed portions of the driving shaft members 33, which are reduced at both ends. On their inner ends, nuts 34 are provided for rigidly securing the crank webs and driving shaft members together.

Instead of the above arrangement, the 20 gaging portions of the crank web and driving shaft members may be formed parallel, keys, pegs or other suitable means being provided for transmitting the driving forces.

The right-hand driving shaft member 33, 25 has a flywheel 35 secured thereon, as shown by means of a nut 36, having a cylindrical extension which serves as a support for the clutch. The drive to the transmission gear is taken from the inner periphery of the flywheel 35. The left-hand driving shaft member 33 has a pulley 37 carrying a sprocket wheel 38, secured thereon, by means of the nut 34, the pulley and sprocket wheel being adapted to drive a cooling fan and a magneto 35 respectively, or it may be any of the other auxiliary mechanism of the motor.

In order to assemble the motor, the piston 8, connecting rod 31, crank pin 30 and crank webs 28 in the assembled condition are introduced into the cylinder-crank case unit 40 through the hole in the crank case, the cap 17 having previously been removed therefrom. The driving shaft members 33, are then pushed through their bushes 18, from 45 opposite ends of the crank case, so that their tapered portions enter the holes in the crank webs 28. The nuts 34 are then screwed on the reduced ends of the members 33 to secure the parts of the crank shaft rigidly to one another, after which the cap 17 may be replaced.

The cover plates 21 are then slipped over the ends of the crank shaft bushings or bearings 18, and on tightening up the nuts on the through-going bolts 26, the assembly of 55 the motor unit is completed by attaching the flywheel, pulley and sprocket wheel.

The lubrication may be effected by means of loose rings 39 which dip into the oil in the 60 annular lubricating chambers 23, at one portion of their circumference while at another portion they contact with the driving shaft members of the crank shaft through an aperture 40 in the bearings or bushes 18. The 65 oil is then led along the crank shaft in both

directions by screw-like channels 41, the inward flow of lubricant being distributed centrifugally to the moving parts in the crank case, while the outward flow is caught by casting 42 on the flywheel 35 and sprocket wheel 38, and returned to the chambers 23 by ducts 43. As an alternative to the above system, pressure-feed or other system of lubrication may be adopted.

In Figures 4 and 5 a twin cylinder motor 75 is shown, constructed in accordance with the invention.

In this arrangement the cylinder crank case units are formed as above described, except that only two end cover plates 21 are 80 necessary, as the intermediate annular extensions 19 on the unit, abut against one another to form an intermediate lubricating chamber 44. One of the cylinder-crank case units has two crank shaft bushings or bearings 18, fixed therein, one of which serves as a 85 bush or bearing for the intermediate driving shaft member 45, and also acts as a register in assembling the other unit thereto. The intermediate driving shaft member 45, 90 of the crank shaft, is provided at each end with nuts 46 for assembling it with the adjoining crank webs 28. The end driving shaft members 33 may be formed as previously described, in the single cylinder arrangement.

In assembling the units the outer driving shaft members are attached to the crank webs of their respective units. One end of the intermediate driving shaft member is 100 then attached to the unit having both bushings or bearings secured thereto, and the other unit assembled therewith, by sliding its bearing support over the intermediate busher bearing projecting from the first unit. 105 The other end of the intermediate shaft member is then attached to the crank web of the second unit.

The two-cylinder-crank case units and the two end cover plates 21 are clamped together by one set of through-going bolts 26.

The short exhaust pipes 10^a, Figure 5, on the cylinder units so assembled are jointed up to one another and clamped firmly between the shoulder 13 and cap 15 on the tube 11, an arrangement which, with a similar arrangement for the induction pipes, imparts additional rigidity to the assembled units.

The open end of the exhaust tube 11 in both the arrangements above described, may 120 be connected to the silencer, similarly, the open end of the induction tube may be attached to the carburetter.

In some cases tubular driving shaft members may be used and when such are used in 125 multi-cylinder motor units flanged screws are provided on the ends attached to the crank webs so as to preserve the isolation of the crank case chambers.

As each cylinder unit is balanced in itself 130

any number of units may be assembled together without further balancing.

5 Motor units having any desired number of cylinders may be assembled together as a single multi-cylinder unit, the method of assembly being similar to the twin cylinder unit.

10 In the foregoing arrangement of single cylinder and multi-cylinder units it will be seen that most of the components are identical the exceptions being the through-going bolts, the induction and exhaust tubes which vary in length according to the number of cylinder crank-case units which are assembled together. The intermediate driving shaft members are interchangeable with one another, and also with the end driving shaft members.

20 By means of the invention it will be seen that single cylinder or multi-cylinder units may be manufactured at a very low cost, and in a very expeditious manner.

25 Although the invention has been described as applied by way of example to a two-stroke motor, its use is not confined to such application as it may readily be adapted to four stroke motors.

30 Further it may be applied to arrangements of motors in which the cylinders are disposed in V, Y, radial or other formation.

35 It is to be understood that the above examples of the invention are simply to be regarded as typical only, and not as in any way restricting the invention to the examples described, as modifications may be made in these examples, without departing beyond the scope of the invention.

I claim:

40 1. An internal combustion engine, including a plurality of cylinder units having interfitting end portions and adapted to be assembled in an engine unit, caps adapted to cover the free ends of the cylinder units at the ends of the engine unit, and means extending through all the cylinder units and the caps for securing said caps and units in engine forming relation.

45 2. An internal combustion engine, including a plurality of cylinder units having the cylinder, crank case, intake and exhaust manifolds formed integral, the crank case, intake and exhaust manifolds thereof being formed for interfitting relation with the respective parts of the adjacent cylinder units and together form an engine unit, a cap for the crank case at each end of the engine unit, means extending through the crank case portions of the cylinder units and the caps for holding said units in engine forming position, and means extending through the intake and exhaust manifold portions for additionally securing the units together.

50 3. An internal combustion engine, including a plurality of cylinder units having the

cylinder, crank case, intake and exhaust manifolds formed integral, the crank case, intake and exhaust manifolds thereof being formed for interfitting relation with the respective parts of the adjacent cylinder units 70 and together form an engine unit, a cap for the crank case at each end of the engine unit, means extending through the crank case portions of the cylinder units and the caps for holding said units in engine forming position, and sleeves extending through the exhaust and intake manifolds having means at the ends of the engine unit for additionally securing said cylinder units together. 80

4. An internal combustion engine, including a plurality of cylinder units, each having the cylinder and the crank case, intake, and exhaust manifolds formed integral therewith, the intake and exhaust manifolds each 85 having a passage communicating with the cylinder, said crank case, intake and exhaust manifolds being formed for interfitting relation with the respective parts of adjacent cylinder units and assembled to form an engine unit, means extending through the units to secure them in engine forming relation, a sleeve extending through the exhaust manifolds, and another sleeve extending through the intake manifolds of the cylinder units forming the engine unit, each sleeve being formed with ports registering with the respective ports in the manifolds of the cylinder units, so that the interior of 90 the sleeves form the exhaust and intake passages respectively of the engine unit, and means carried by the sleeves at the ends of the engine unit for additionally securing the cylinder units together. 95

5. An internal combustion engine, including a plurality of cylinder units assembled to form an engine unit, each unit having the cylinder and crank case formed integral and the ends of the crank case formed to register with the corresponding ends of the crank cases of adjoining units, the crank case of each unit being formed with partition walls spaced from the ends thereof and from each other to provide a central compartment for housing the crank shaft and webs of the unit, and open end compartments adapted to form lubricant containing chambers with the end compartments of adjacent units, crank shaft bearings mounted in said partition walls, crank shafts rotatable in said bearings, and means whereby lubricant contained in said lubricating compartments is constantly fed to said crank shafts. 105

10. 6. An internal combustion engine, including a plurality of cylinder units having the crank case of each unit formed at each end to register with the corresponding ends of the crank cases of adjacent units, the crank case of each unit being also formed with partition walls spaced from each other and 110 115 120 125 130

the ends of the unit to form a central housing for the movable parts of the cylinder unit, and the outer ends being open and adapted to form a lubricating chamber with the open ends of adjacent cylinder units, and means for assembling the units in engine forming relation.

7. An internal combustion engine, including a plurality of cylinder units having the crank case of each unit formed at each end to register with the corresponding ends of the crank cases of adjacent units, the crank case of each unit being also formed with partition walls spaced from each other and the ends of the unit to form a central housing for the movable parts of the cylinder unit, and the outer ends being open and adapted to form a lubricating chamber with the open ends of adjacent cylinder units, the crank case of each unit being further formed at the sides thereof with double walls, the space between the walls opening into the lubricating chambers thereof, and means for assembling the units in engine forming relation.

8. An internal combustion engine, including a plurality of cylinder units having the crank case of each unit formed at each end to register with the corresponding ends of the crank cases of adjacent units, the crank case of each unit being also formed with partition walls spaced from each other and the ends of the unit to form a central housing for the movable parts of the cylinder unit, and the outer ends being open and adapted to form a lubricating chamber with the open ends of adjacent cylinder units, said cylinder units being assembled to form an engine unit, caps for covering the open ends of the crank case at the ends of the engine unit, means extending through the caps and cylinder units for holding them in engine forming relation, and means formed on the cylinder units for supporting said units and the engine unit.

9. An internal combustion engine, including a plurality of cylinder units, each unit having a crank case formed so that the end portions thereof are adapted to register with corresponding end portions on adjacent units, partition walls formed in the crank case, said walls having aligned openings, a crank shaft bearing mounted in the opening in one wall of one unit and projecting beyond the end of the crank case of the unit, the projecting end of the bearing fitting in the opening in the wall of the adjacent cylinder unit, whereby the bearing forms a means of centering adjacent cylinder units in forming an engine unit, and means for securing the units in assembled engine forming position.

10. An internal combustion engine, including a plurality of cylinder units adapted to be assembled in engine forming relation, each

cylinder unit having a crank case provided with partition walls, each crank case being formed on its outer sides with means to register with the ends of similar means on adjacent crank cases, means carried by a partition wall in the crank case of one unit adapted to cooperate with an adjacent partition in the adjoining unit for relatively positioning one cylinder unit with respect to the other, and means for securing the cylinder units in engine forming relation.

11. An internal combustion engine, including a plurality of cylinder units adapted for interfitting relation to form an engine unit, said cylinder units being formed with intake and exhaust casings also adapted to register with the respective parts of adjacent units, and means extending through the aligned casings of the engine unit and cooperating therewith to form an intake and exhaust manifold and for securing the cylinder units together.

12. An internal combustion engine, including a plurality of cylinder units adapted for interfitting relation to form an engine unit, each cylinder unit having an inlet and exhaust casing formed therewith and registering with the corresponding parts of adjacent units, and a sleeve for each of the aligned casings, each sleeve extending throughout all the units in the respective casing and cooperating therewith to form an intake and exhaust manifold.

13. An internal combustion engine, including a plurality of cylinder units having interfitting end portions and adapted for assemblage to form an engine unit, and means extending through all the cylinder units for securing said units in engine forming relation.

14. An internal combustion engine, including a plurality of cylinder units having interfitting end portions and inlet and exhaust casings adapted to be assembled in an engine unit, the inlet and exhaust casings of all the units being in respective alignment, means extending through all the cylinder units for securing the units together, and additional means extending through the intake and exhaust casings for securing said units together and cooperating respectively with the intake and exhaust casings to form manifolds.

15. An internal combustion engine having end walls, bearings mounted in the end walls and projecting therefrom, flanges projecting outwardly from the end walls, a crank shaft mounted in the bearings and caps fitting over the flanges and provided with openings to receive the projecting portions of the bearings, said caps and end walls between the flanges forming lubricant chambers surrounding said bearings.

16. An internal combustion engine having end walls, bearings mounted in the end walls and projecting therefrom, flanges projecting

outwardly from the end walls, a crank shaft mounted in the bearings and caps fitting over the flanges and provided with openings to receive the projecting portions of the bearings, 5 and means common to the caps and the engine for securing said caps and engine together.

17. An internal combustion engine, including a plurality of cylinder units adapted for

interfitting relation to form an engine unit, 10 each cylinder unit being formed with a casting adapted to register with similar castings on adjacent units, and means extending through aligned casings to form a manifold and for securing the cylinder units together. 15

In testimony whereof I have signed my name to this specification.

GEORGE HALL-BULLOCK.
